CLAIM

The ornamental design for a needle point panel shoe insert, as shown and described.

DESCRIPTION

FIG. 1 is a perspective view of a needle point panel shoe insert according to my new design.

FIG. 2 is another perspective view of the needle point panel shoe insert according to my new design.

FIG. 3 is a top view of the needle point panel shoe insert according to my new design.

FIG. 4 is a right view of the needle point panel shoe insert according to my new design.

FIG. 5 is a left view of the needle point panel shoe insert according to my new design; and,

FIG. 6 is a front view of the needle point panel shoe insert according to my new design.

The broken lines in the figure views depict portions of the shoe insert that form no part of the claimed design.

1 Claim, 6 Drawing Sheets
